HYDRAULIC JACK FOR REMOVING ROCK DRILL STEELS

Charles E. Gonser and Cecil D. Hingley,
Denver, Colo.

Application April 2, 1935, Serial No. 14,200

1 Claim. (Cl. 254—30)

This invention relates to a jack for removing stuck rock drills from the drill holes and has for its principal object the provision of a hydraulic jack construction which will allow the jack to be placed over and around the protruding extremity of a stuck drill steel so as to exert a direct upward pull thereon to remove the steel from the hole.

Another object is to provide means for gripping the drill steel at any desired point throughout its length so that a ratchet-like action can be used to remove a long drill steel.

A further object is to so construct the device that an exceedingly great pull can be applied with a minimum of manual effort.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 is a plan view of the improved drill steel pulling jack.

Fig. 2 is a vertical section therethrough, taken on the line 2—2, Fig. 1.

Fig. 3 is a similar view illustrating the jack in the partially raised position.

The invention comprises a base 10, upwardly from which, three concentric cylinders extend. The cylinders consist of an inner cylinder 11, which preferably extend entirely through the base 10, and an outer cylinder 12, surrounded by a reservoir cylinder 13.

All of the cylinders are liquid tight to the base 10 and the cylinders 12 and 13 are closed to each other at the top and spaced apart to form a fluid reservoir. The cylinders 11 and 12 are spaced apart to form an annular pressure chamber into which a cylindrical jack plunger 14 projects.

The plunger 14 terminates in a head 15 at its top and in a suitable packing washer 16 at its bottom. A conical hole 17 is formed concentrically through the head 15 for receiving split conical gripping dogs 18. Channels in the inner faces of the dogs provide a passage for the drill steel. The grooves are formed with ratchet-like gripping teeth 30.

A fluid pressure pump 19 is mounted on the base 10 and provided with a suitable operating handle 20. The handle 20 reciprocates a pump

piston 21 in the pump 19. A feed passage 22 extends from the pump to the fluid reservoir between the cylinders 12 and 13. The passage 22 is controlled by means of a suitable check valve 23. A pressure passage 24 leads from the pump 19 to the pressure chamber between the cylinders 11 and 12. The pressure passage is controlled by means of a suitable check valve 25. A by-pass passage 26 communicates between the two passages 22 and 24, and is controlled by means of a suitable needle valve 27.

In Fig. 3, a typical rock drill steel is indicated at 28. Let us assume that this steel is stuck in the drill hole of a rock surface 29 so that it cannot be removed by ordinary methods. To apply the invention thereto, it is only necessary to set the entire jack over the projecting drill steel 28, with the steel extending upwardly through and protruding from the inner cylinder 11. The two split dogs 18 are then dropped into the conical opening 17 in the head 15 at each side of the steel.

The pump 19 is now operated to force fluid from the reservoir into the pressure chamber. This fluid raises the jack plunger 14, causing the dogs 18 to wedge themselves between the conical sides of the opening 17 and the drill steel so as to force the teeth 30 into the latter. Further upward movement of the plunger withdraws the steel from the drill hole in the rock 29.

If the steel is not loosened after being elevated the full height of the jack, the needle valve 27 is opened. This allows the fluid to flow from the pressure chamber through the bypass 26 and back to the reservoir, and allows the head 15 to lower by gravity. The first lowering movement of the head acts to release the dogs 18 from the drill steel owing to the conical shape of the hole 17 so that the dogs will slide downwardly along the steel. The pump is now actuated to cause the dogs to again grip the steel and elevate the latter. This process, of course, can be continued until the entire steel has been withdrawn from the hole.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:—

A hydraulic jack for withdrawing rock drill steel comprising in combination: a base; a first

cylinder extending through said base and projecting above the top thereof; a second cylinder concentrically surrounding said first cylinder and extending upwardly from the top of said base; a third cylinder concentrically surrounding the other cylinders and extending upwardly from the top of said base; means for sealing the upper extremities of said second and third cylinders together; a cylindrical plunger slidably mounted 5 between said first and second cylinders; a head 10 on said plunger having an axial opening in align-

ment with the hollow interior of said first cylinder; clamping members in said opening; a pump mounted on said base; a conduit extending from said pump to the space between said first and second cylinders; a second conduit from the space between said second and third cylinders to said pump; a bypass passage communicating between said two conduits; and a valve for controlling said bypass passage. 5
